UNITED STATES PATENT OFFICE.

MAXIMILIAN CHARLES SCHWEINERT, OF WEST HOBOKEN, NEW JERSEY, AND
HENRY P. KRAFT, OF NEW YORK, N. Y.

WATER-BOTTLE STOPPER.

955,441.

Specification of Letters Patent. Patented Apr. 19, 1910.

Application filed July 5, 1907. Serial No. 382,222.

To all whom it may concern:

Be it known that we, MAXIMILIAN CHARLES SCHWEINERT, residing in West Hoboken, in the county of Hudson and State 5 of New Jersey, and HENRY P. KRAFT, residing in the borough of Brooklyn, county of Kings, city and State of New York, citizens of the United States, have invented certain new and useful Improvements in Water- 10 Bottle Stoppers, of which the following is a specification.

This invention relates to water bottle stoppers and aims to provide certain improvements therein.

15 The invention is particularly directed to a form of stopper in which the packing washer is held by a plate secured to the bottom of the stopper. Such a stopper is illustrated in our Patent No. 902,259, dated 20 October 27, 1908.

The present invention is particularly directed to the means for attaching the retaining device to the stopper.

In the drawings which illustrate one form 25 of our invention, Figure 1 is a vertical section of the mouth of a hot water bottle having a stopper provided with our invention; Fig. 2 is a bottom view of the stopper detached; Fig. 3 is a sectional view illustrating the several parts of the stopper detached before the assembling operation.

30 Referring to the drawings, let A indicate the neck of a hot water bottle having vulcanized therein or otherwise attached thereto 35 a screw-threaded socket member B having a seat C.

D indicates the stopper which is provided with external threads which engage the socket member B. The stopper D carries 40 at its lower end a packing washer or disk E which is confined in place by an annular plate F, the stopper being provided with an integral projecting portion G which engages the inner flange of the plate F. In 45 constructing the stopper, the body portion is first drawn into the form of a stopper having a cylindrical projecting portion at its bottom as indicated in Fig. 3. The plate F is then applied to the stopper so that such 50 projecting portion enters the central aperture of the plate, whereupon it is upset so as to engage the plate, as shown in Fig. 1. The disk or washer E is then sprung in

place between the plate and the bottom of the stopper.

According to the present invention we utilize the plate F or its equivalent to connect a retainer such as H to the stopper. Preferably in the operation of striking up the plate F we form a lug I at its bottom and bend such lug downwardly at right angles to the lower flange of the plate, and so form the lug that it is capable of engagement with the retaining device. In the construction shown it is provided with a hole J adapted to receive the end of the retainer H. Obviously, however, the plate can be provided with other means for engaging the retainer.

The retainer H is shown as comprising a chain having at its end a wire ring K which is of such diameter as to prevent its passing through the seat C without distortion. We prefer to provide the retainer at its upper end with a split ring L which is formed as a key ring. By this means the retainer may be attached to the stopper or detached therefrom by hand. This construction also enables the retainer to be conveniently made and sold as a separate article of manufacture since it can be applied to the stopper by any ordinary person without the use of a tool. In the construction shown the ring K is of sufficient elasticity to permit it being forced through the seat of the stopper, while it possesses sufficient rigidity to prevent it escaping therefrom under the ordinary conditions of use. Any other form of retainer which is suitable for the purpose may, however, be used.

While we have shown in detail one form of our invention, it will be understood that various changes may be made therein without departing from the invention. For instance, the plate F need not be in the form illustrated, and it may be attached to the stopper in other ways than that shown.

We do not herein claim the construction of retaining device shown. Devices of this type are set forth in applications Nos. 181,253, filed Nov. 3, 1903, and 318,742, filed May 25, 1906.

What we claim is:—

1. In a water bottle stopper or the like, a packing washer, a plate adapted to hold such washer in place, such plate being per-

manently connected to the stopper body by a part which is formed separately from such plate, and a retainer connected with such plate.

2. In a water bottle stopper or the like, a packing washer, a plate adapted to hold such washer in place, such plate being permanently connected to the stopper body by a part which is formed separately from such plate, and such plate having means for engaging a retainer.

3. In a water bottle stopper or the like, a packing washer, a plate adapted to hold such washer in place, such plate being permanently connected to the stopper body by a part which is formed separately from such plate, and such plate having means for engaging a retainer, and a retainer connected with such means.

4. In a water bottle stopper or the like, a packing washer, a plate adapted to hold such washer in place, such plate being permanently connected to the stopper body by a part which is formed separately from such plate, such plate having a lug struck up from its body, and a retainer connected to such lug.

5. The combination of a stopper having an integral projecting portion at its bottom, an annular plate surrounding such projecting portion and connected to the stopper body thereby, a packing washer between said

plate and said stopper body, a perforated lug struck up from the body of said plate, and a retainer connected to said lug. 35

6. The combination of a stopper having an integral projecting portion at its bottom, a separately formed plate connected to the stopper body by such portion, a packing washer between said plate and body and a retainer connected to such plate. 40

7. The combination of a stopper having an integral hollow projecting portion struck from its bottom, a separately formed plate connected to the stopper body by such portion, a packing washer between said plate and body and a retainer connected to such plate. 45

8. The combination of a stopper having an integral projecting portion at its bottom, a separately formed plate connected to the stopper body by such portion, a packing washer between said plate and body, a retainer and a split ring connecting said retainer to said plate. 50

In witness whereof, we have hereunto signed our names in the presence of two subscribing witnesses.

MAXIMILIAN CHARLES SCHWEINERT.
HENRY P. KRAFT.
